(57) **CLAIM**

The ornamental design for a housing for a centrifuge, as shown and described.

DESCRIPTION

FIG. 1 is a perspective view of a housing for a centrifuge; FIG. 2 is a left side view of FIG. 1; FIG. 3 is a right side view of FIG. 1; FIG. 4 is a top view of FIG. 1; FIG. 5 is a bottom view of FIG. 1; FIG. 6 is a front view of FIG. 1; and, FIG. 7 is a rear view of FIG. 1.

The broken lines in the drawings depict portions of the housing for a centrifuge which form no part of the claimed design.
